UNITED STATES PATENT OFFICE.

EDWIN J. GROSS, OF ALLENTOWN, PENNSYLVANIA, ASSIGNOR OF ONE-HALF TO EDWIN J. LICHTENWALNER, OF ALLENTOWN, PENNSYLVANIA.

MEANS FOR OPERATING RAILROAD SWITCHES OR TARGETS.

SPECIFICATION forming part of Letters Patent No. 760,447, dated May 24, 1904.

Application filed November 4, 1903. Serial No. 179,842. (No model.)

To all whom it may concern:

Be it known that I, EDWIN J. GROSS, of Allentown, in the county of Lehigh and State of Pennsylvania, have invented certain new and useful Improvements in Means for Operating Railroad Switches or Targets; and I do hereby declare the following to be a full, clear, and exact description of the invention, such as will enable others skilled in the art to which it applies to make and use the same.

The object of this invention is to provide improved, simple, and highly-efficient means for operating switches and signal-targets of a railway from moving cars without the necessity of stopping the car and avoiding hand manipulation of the actuating mechanisms by the motorman or conductor.

The invention will be hereinafter fully set forth and particularly pointed out in the claims.

In the accompanying drawings, Figure 1 is a plan view of a bottom of a car equipped with operating means in accordance with my invention. Fig. 2 is a side view of a portion 25 of a car at the center thereof. Fig. 3 is an enlarged sectional view showing a trip-actuating wheel and means for controlling the same. Fig. 4 is a diagrammatical view of sections of a railroad equipped with my improvements. Fig. 5 is an enlarged cross-sectional view on line 5 5, Fig. 4. Fig. 6 is a view on line 6 6, Fig. 5.

Referring to the drawings, 1 designates a car-body, and 2 a shaft at about the center thereof, equipped with wheels 3, engaged by chains 4, (or it may be rods,) leading from operating-levers 5 on the end platforms. On this shaft are segmental toothed wheels 6, which mesh with rack-bars 7, vertically movable in guides 8. These rack-bars at their lower ends support a cross rod or shaft 9, on the ends which are trip-actuating wheels 10, the flanges 12 of which are on the outer sides thereof, while the flanges of the car-wheels 13 are, as usual, on the inner sides. The shaft 2 is equipped with a counterbalancing-weight 14 to offset the weight of the trip-actuating wheels and their controlling mech-

anism. By operating either lever 5 these actuating-wheels may be lowered or raised at 50 will; but they are normally held in the position shown in full lines in Fig. 2.

In Fig. 4 I have shown at 15 the point of location of a target and have also shown trips 16, one being adjacent the main-line track 17, while the other adjoins the turnout-track 18. I have shown at 19 a trip for actuating the switch 20, so that a car moving in the direction of arrow X will set the switch to allow the car to pass onto the turnout, 60 while at 21 is a trip for returning the switch to its normal position by a car moving in the opposite direction, such latter trip being located on the inside of the track between the rails thereof. Each of the other trips, it 65 will be noted, is located outside of the track-rails, and hence are in line to be actuated by wheels 10, whereas trip 21 will be actuated by the flanges of the car-wheels. The construction and operation of each trip will be 70 readily understood from Figs. 5 and 6. In a housing 22 is located a spring-plate 23, paralleling the tread of the rail, against which it is closely set, such plate being centrally mounted on an upright rod 24, passed downwardly 75 through a sleeve 25 and connected by suitable cranked rods 26 or other means to the mechanisms of the target or switch, as the case may be. When the plate 23 of any one of the trips is depressed by the actuating-wheel 80 of a passing car, the mechanism of the target or switch is set and there remains until the complementary trip is operated, there being two trips to a target and also to the switch.

In practice as a car traveling in the direction of arrow Y, Fig. 4, approaches the target the motorman will throw lever 5 so as to lower the actuating-wheels 10, one of which will depress plate 23 of trip 16 of the main-line track, thereby throwing off the light or 90 target, so that the motorman of the next car will be apprised of his right of way. A car going in the opposite direction will likewise operate the target. With a car approaching the switch in the direction of arrow X the motorman desiring to go onto the turnout throws 95

one of the levers 5, so that the trip 19 will be actuated to set the switch, and the presence of his car on the turnout will be indicated by the target, which is operated by the actuating-wheels of his car engaging the other of the trips 16—that is, the one adjacent the outer rail of the turnout. A car on the main track going in the opposite direction (indicated by arrow Y) again throws the switch into its proper place by the flanges of its wheels engaging the trip 21.

From what has been said it will be seen that I have provided in a block signal and switch system extremely simple and highly-efficient means for actuating the target and switches of electric railways directly from a moving car.

It is obvious that any suitable means may be employed for connecting the several trips with the actuating mechanisms of the targets and switches and also that suitable provisions may be made to protect such connecting means and to guard against danger from ice, snow, &c.

25. I claim as my invention—

1. The combination with a car, of trip-actuating wheels, a shaft therefor, a second shaft connected to the first-mentioned shaft and having means for normally holding the latter raised, and means for actuating said second shaft for lowering the first-mentioned shaft from either end of a car, as set forth.

2. The combination with a car, of trip-actuating wheels, a shaft therefor, a second shaft, means connecting said shafts for raising and lowering the first shaft, means for actuating such second shaft from the ends of a car, and trip mechanisms for targets or switches designed to be engaged by said actuating-wheels, as set forth.

3. The combination with a car, of trip-actuating wheels, a shaft therefor, a second shaft having toothed wheels, rack-bars secured to the first-mentioned shaft and engaged by said toothed wheels, guides for said rack-bars,

means for actuating said second shaft from the ends of a car, and trip mechanisms for targets or switches designed to be engaged by said actuating-wheels, as set forth.

4. The combination with a railroad-track, 50 targets or switches, and trips for the latter having engaging portions located adjacent to, but outside of, the track-rails, of a car having a shaft capable of being moved vertically, means for actuating such shaft, and wheels 55 mounted on the ends of such shaft having flanges at their outer sides for engaging said trips, as set forth.

5. The combination with a railroad-track, 60 targets or switches, and trips for the latter having engaging portions located adjacent to, but outside of, the track-rails, of a car having a shaft, wheels mounted thereon having outer flanges for contacting with said engaging portions of the trips, rack-bars secured to such 65 shaft, a counterbalanced shaft having toothed wheels meshing with said rack-bars, and means for actuating such shaft from the ends of a car, as set forth.

6. The combination with a railroad-track, 70 a turnout and a switch therefor, of two trips for actuating such switch, each trip having an engaging-plate, one trip being located outside of the track and the other trip between the rails thereof, such latter trip being designed to be engaged by the carrying-wheels 75 of a car, a car movable on such track having an actuating-wheel equipped with a flange on its outer side for contacting with the engaging-plate of the outer trip, and means for controlling the position of such actuating-wheel, substantially as set forth.

In testimony whereof I have signed this specification in the presence of two subscribing witnesses.

EDWIN J. GROSS.
